Primary Examiner — Kendra Leslie Hamilton*(74) Attorney, Agent, or Firm* — Muncy, Geissler, Olds & Lowe, P.C.**CLAIM**

The ornamental design for a pet leash, as shown and described.

DESCRIPTION

FIG. 1 illustrates a pet leash according to the present invention.

FIG. 2 is a perspective view of the pet leash of FIG. 1, shown in a first condition of use; and,

FIG. 3 is a perspective view of the pet leash of FIG. 2, shown in a second condition of use and enlarged for clarity of disclosure.

The broken line showing of a leash, leash handle and related elements depicts portions of the pet leash that form no part of the claimed design. The broken lines showing a dog, chair and column in FIGS. 2 and 3 depict environmental structure that forms no part of the claimed design. All broken lines form no part of the claimed design.

1 Claim, 3 Drawing Sheets(56)
